UNITED STATES PATENT OFFICE.

JOHN BAUER, OF DETROIT, MICHIGAN.

STORM-SHIELD.

1,354,374.

Specification of Letters Patent. Patented Sept. 28, 1920.

Application filed January 16, 1920. Serial No. 351,764.

To all whom it may concern:

Be it known that I, JOHN BAUER, a citizen of the United States, residing at Detroit, in the county of Wayne and State of Michigan, have invented a new and useful Storm-Shield, of which the following is a specification.

This invention relates to storm shields, and has for its object the provision of a device that may be attached during a storm to the ordinary wind shield now in use on automobiles, to prevent snow and rain accumulating on the glass of the wind shield and obscuring the vision of the driver of the car.

Another object is to so construct the device that it may be folded into small compass when not in use and quickly reassembled when required.

With these and other objects in view as will appear as the description proceeds, the invention resides in the combination and arrangement of parts to be more fully described and particularly pointed out in the appended claims, it being understood that changes may be made in the device within the scope of what is claimed without departing from the spirit of the invention, or sacrificing any of the advantages thereof.

In the drawings forming a part of this specification, like characters of reference refer to like parts through the several views in which drawings,

Figure 1 is a view in side elevation of a storm shield constructed in accordance with this invention.

Fig. 2 is a view in side elevation of the device when folded.

Fig. 3 is a view in front elevation.

Fig. 4 is a fragmentary sectional view taken on line 4—4 of Fig. 1.

Fig. 5 is a similar view taken on line 5—5 of Fig. 1.

Fig. 6 is a detail sectional view taken on line 6—6 of Fig. 1.

Fig. 7 is a view in side elevation of a modification.

Fig. 8 is a side elevation of a still further modification.

Fig. 9 is a section on line 9—9 of Fig. 8.

Fig. 10 is a detail view of a brace.

Fig. 11 is a modified form of shield.

Fig. 12 is a still further modification.

Referring to the drawing, the numeral 1 designates a wind shield of usual construction having the frame 2 supporting the glass plate 3.

The device forming the subject matter of this application comprises two end frame members which are secured to the ordinary wind shield 1, and comprises two vertical members 4, a top bar 5, and a bottom bar 6. As the frame at one side is practically a duplicate of that at the other side, it is thought a detailed description of one will suffice for a clear understanding of the device.

The vertical member 4 is composed of two pieces connected by a slot and pin connection 7 for longitudinal adjustment, and is provided along one edge with a rubber buffer strip 8 for engaging the glass of the wind shield to seal the joint and prevent rattle. The upright 4 is secured to the wind shield frame 2 by means of straps or bands 9. A hook 10, to which the inner end of the member 5 is pivoted, engages the top of the frame 2 and supports the weight of the entire structure.

A rod 11 connects the two side members 4 of the shield and forms the pivotal connection between the members 5 and 10. The upper bar 5 projects forwardly and is inclined downwardly over the engine hood and comprises a channel member having downturned flanges 12 and 13. A groove 14 is formed along the upper inner edge of the channel member, which groove supports a curtain 15 to form the top of the storm shield. The curtain 15 is mounted at its inner end on a spring roller 16, which is supported on brackets 17 fixed to the flange 13.

The lower bar 6 is pivoted to the upright 4 and projects outwardly and upwardly beneath the upper member 5, the bar having upturned flanges 18 and 19. A groove 20 is formed on the inner flange 19 and supports a closure 21 for the bottom of the storm shield. As shown the member 21 may be a plate of glass, celluloid, or other transparent material or may be a curtain similar to the top closure 15. A rod 11' connects the lower ends of the uprights 4 and also forms the pivotal connection between the members 4 and 6.

The sides of the shield may be closed by

a series of plates 22, the longer of which are provided with slot and pin connections 23, whereby the individual slats may be shortened for storage.

- 5 Each slat has at its upper and lower end an outwardly projecting pin or lug 24, which is adapted to engage one of a series of lugs 25 formed on the flanges 12 and 18 of the respective bar members 5 and 6. The 10 slats 22 are arranged in the channels 5 and 6, with their edges overlapping as shown in Fig. 4, each slot having its lug 24 resting against a respective stop 25. To hold the slats 22 in place in the bars 5 and 6 rods 26 15 and 27 are provided, the same being pivoted to the ends of the casing 5 and shaped to form crank arms which engage the slats and force them into engagement with the flanges 12 and 18. The flange 18 is provided with 20 grooves 28 which are adapted to receive lugs 29 formed on the slats 22 and which further assist in retaining the slats in position.

The bar 6 may be provided intermediate its ends with a hinge joint 30, that the same 25 may be folded to enter the channel 5 for storing the same.

A link 31 is pivoted to the bar 6 at its outer end, the link having a hook for engaging a pin 32 on the bar 5, the link serving to preserve the spaced relation of the 30 bars 5 and 6. The outer ends of the curtain 15 are secured by means of straps 33 to the bars 5. The straps holding the curtain against the tension of the spring roller 16 35 to retain the same in a taut position.

Automobiles are sometimes provided with an auxiliary wind shield which projects forwardly and downwardly from the top of the vertical wind shield. To provide for the 40 attachment of the storm shield to a wind shield of the above type clips 34 are secured to the bars 5 and are provided with wing bolts 35 for clamping the storm shield to the auxiliary wind shield. In the modification 45 shown in Fig. 7, top and bottom bars 36 and 37 have pivoted thereto a series of overlapping slats 38 each slat being in two parts and pivoted as at 39 to a horizontal bar 40, whereby the entire panel may be folded by 50 a pull on the handle 41 of the bar, the slats having a limited swinging movement at their pivotal points on the bars 36, 37 and 40.

In Figs. 8 and 9 another modification is 55 shown in which the top and bottom bars 42 and 43 are provided with a retaining device 44 similar to the bail 27, whereby a curtain 45 is supported in the bars for closing the sides of the storm shield. The top 60 bar 42 is provided with a slot 46 for retaining a curtain 47 in place to close the top of the shield and a slot 48 in the bar 43 supports the lower closure plate 49. The curtain 45 is mounted on a spring roller 50 at 65 one end and held in extended position by

straps 51 which are secured to projections 52 formed on a brace bar 53. The said bar is similar to the bar 31 and spaces the bars 42 and 43 at their outer ends. Buttons 54 are mounted on the bar 5, so that an auxiliary 70 cover may be attached to the storm shield if necessary, or may take the place of the curtain 15 if desired.

Briefly considered the storm shield constituting the subject matter of this invention comprises a frame made up of the upright members 4 on either side of the shield and connected by the rods 11 and 11', this frame being supported from the ordinary wind shield or other means of support; a 75 top comprising the bars 5 on either side and the curtain 15; a bottom which includes the bars 6 and the bottom plate 21; the links 31 for spacing the top and bottom, and the side 80 panels 22.

Although primarily intended as a shield to be used in connection with an automobile it is to be understood that the device herein disclosed may be employed for other uses such for instance as the protection of show 90 windows or the like against the accumulation of rain or snow thereon.

Other uses to which the storm shield may be adapted will present themselves, among which is its application as a shield for the 95 front of street and interurban electric cars, locomotives, steam boats, ships and all kinds of air craft.

Fig. 11 illustrates a slightly modified form of mounting for the side rails. In 100 this form the rails 5' are hingedly connected to members 10' as shown at 11'', so that the rails 5' may be folded as shown in dotted lines, across the front of the wind shield, to occupy this position when not in 105 use and be immediately available when needed.

Fig. 12 illustrates means for rendering the storm shield more secure against entrance of the weather. A flange 55 of transparent material may be fitted to the inner edge of the storm shield to rest against the glass of the ordinary wind shield and in this way insure contact over a larger surface of the glass of the wind shield thereby 110 making the shield practically air tight around the edges of the shield. It will be understood that illustration of the storm shield in Fig. 12 is only diagrammatical.

Having thus described the invention, 120 what is claimed is:—

1. In a device of the class described, a frame provided with support-engaging means, a top pivotally supported at its rear end on the upper portion of the frame, a bottom pivotally supported at its rear end on the lower portion of the frame, a latch forming a releasable connection between the outer ends of the top and bottom and constituting a brace holding the top and bot- 130

- tom against pivotal movement and movable sides extended between the top and the bottom.
2. In a device of the class described, a frame provided with support-engaging means, a top pivotally supported at its rear end on the upper portion of the frame, the top comprising a pair of channel members having grooves formed on their inner edges, a closure for the top, said closure mounted for slidable movement in the grooves, a bottom pivotally supported at its rear end on the lower portion of the frame, a latch forming a releasable connection between the outer ends of the top and bottom and constituting a brace holding the top and bottom against pivotal movement and movable sides extended between the top and the bottom.
- 10 3. In a device of the class described, a frame provided with support-engaging means; a top pivotally supported at its rear end on the upper portion of the frame, a bottom pivotally supported at its rear end on the lower portion of the frame, the bottom comprising a pair of spaced channel members having grooves formed on their inner edges, a bottom closure supported in the grooves, a latch forming a releasable connection between the outer ends of the top and bottom and constituting a brace holding the top and bottom against pivotal movement and movable sides extended between the top and bottom.
- 15 4. In a device of the class described, a frame provided with support-engaging means, a top pivotally supported at its rear end to the upper portion of the frame, a bottom pivotally supported at its rear end on the lower portion of the frame, the bottom comprising a pair of bars, each bar being hingedly connected intermediate its ends for folding movement, grooves formed on the inner face of the bars, and a plate removably supported in the grooves a latch forming a releasable connection between the outer ends of the top and bottom and movable sides extended between the top and the bottom.
- 20 5. In a device of the class described, a frame provided with support-engaging means, a top pivotally supported at its rear end on the upper portion of the frame, a bottom pivotally supported at its rear end on the lower portion of the frame, the top and bottom having side bars comprising channel members, foldable sides extended between the top and bottom and supported in the said channels and means for locking the sides in the channel members.
- 25 6. In a device of the class described a frame provided with support-engaging means, a top pivotally supported at its rear end on the upper portion of the frame, a bottom pivotally supported at its rear end on the lower portion of the frame, the top and bottom having side bars comprising channel members, foldable sides mounted in the channel members and gripping bars eccentrically mounted in the top and bottom bars for releasing the sides of the shield in the said channels.
- 30 7. In a device of the class described, a frame provided with support-engaging means, the frame having upper and lower portions adjustably connected for longitudinal movement, a top pivotally supported at its rear end on the upper portion of the frame; a bottom pivotally supported at its rear end on the lower portion of the frame, the top and bottom being disposed in convergent relation, a latch forming a releasable connection between the top and bottom and movable sides extended between the top and bottom.
- 35 8. In testimony that I claim the foregoing as my own, I have hereto affixed my signature in the presence of two witnesses.
- 40 JOHN BAUER.
